DISTRIBUTOR CAP

James L. Arthur, Ind., assignor, by
means assignments, to General Motors Cor-
poration, Detroit, Mich., a corporation of Dela-
ware

Application March 3, 1936, Serial No. 432,893
Renewed May 19, 1934

12 Claims. (Cl. 266—19)

This invention relates to improvements in terminal heads particularly adapted to be used in the distributor unit of ignition systems for internal combustion engines.

5 It is among the objects of the present invention to provide a terminal head of an ignition device in which condensed vapors are substantially prevented from causing short circuits between any of the terminals thereon.

10 Further objects and advantages of the present invention will be apparent from the following description, reference being had to the accompanying drawing wherein a preferred embodiment of one form of the present invention is clearly shown.

In the drawing:

Fig. 1 is a top plan view of a terminal head for an ignition device.

Fig. 2 is a flat sectional view taken along the line 2—2 of Fig. 1.

20 Fig. 3 is an inverted plan view of the distributor head.

Fig. 4 is a fragmentary sectional view taken through the center of the distributor head along the line 4 of Fig. 1.

Fig. 5 is a fragmentary detail sectional view taken along the line 5—5 of Fig. 2.

Fig. 6 is a fragmentary sectional view taken along the line 6—6 of Fig. 3.

30 Fig. 7 is a fragmentary sectional view taken through the center of the distributor head along the line 7 of Fig. 3.

Fig. 8 is an enlarged view of a furrow provided in the distributor head and showing how the 35 moisture or condensed vapors are confined to certain areas.

Distributor caps or heads for ignition devices for multi-cylinder internal combustion engines usually comprise an insulating body having a central terminal which is adapted to be connected with the high tension windings of an ignition coil. About this central terminal are arranged other terminals, preferably in a circular row, which are respectively adapted to be connected with the 40 spark plugs of the engine. A rotating conductor intermittently connects the central terminal with the respective other terminals in proper sequence thereby to distribute sparking impulses from the ignition coil to the various engine spark plugs.

45 Ignition devices of this type, if provided with a flat, interior surface from which the terminals extend, may have these terminals short circuited by the formation of a film of moisture or condensed vapor, thus rendering the device ineffec-

tive properly to distribute the sparking impulse to the cylinders of the engine.

Applicant guards against such a contingency by providing his distributor cap or head with a 5 sulcated, interior surface from which his terminals extend. The sulcated surface provides intervening furrows between the various terminals, said furrows substantially preventing the formation of a complete film of moisture or condensed vapor between terminals. The furrows 10 form alternate grooves and ridges, which, if of sufficient depth, will substantially prevent the moisture from creeping along the sides of the furrows to their bottom, thus a dry area is provided in the bottom of each furrow which acts 15 as a barrier to the short circuiting of the sparking impulses.

Referring to the drawing, the numeral 20 designates the distributor cap or head, made up of any suitable insulating material, preferably of 20 a condensation product such as bakelite or the like. This distributor head carries a plurality of terminals, 21 designating the central terminal about which the other terminals 22 are arranged in a circular row equally spaced from each other. 25 The inner ends of the terminals extend from the inner surface of the distributor head. On diametrically opposite sides of the distributor cap 20, recesses 23 are provided, forming seats for receiving any suitable means by which the cap is 30 secured to the ignition device. As shown in Fig. 1, these recesses 23 are intermediate two terminals 22.

The inner surface of the distributor cap 20 is 35 sulcated, presenting a plurality of annular wedge-shaped furrows designated by the numerals 25, 26 and 27. As shown in the enlarged view in Fig. 8, the furrows are wedge-shaped, being greater in depth than in width. If the space within the distributor cap between the terminal 21 and the 40 terminals 22 were flat, it will readily be seen that condensed vapors could gather on this surface and form a continuous conducting film between said terminals, thereby effecting the operation of the device detrimentally. In the present instance, however, the furrows will not permit such a conducting film to be completed, for, as shown in Fig. 8, the condensed vapors represented by the small circles 28 will gather on the ridges formed by the furrows and more particularly adjacent 45 the crest of the ridges. The moisture or condensed vapors will gradually enter the furrow along the diverging walls of the ridge between the adjacent furrows. However, the depth of the furrow will not permit the moisture to travel 50

55

along the wall of the furrow to the extreme bottom of said furrow, thus there will be provided a comparatively dry area in the furrow designated by the numeral 29 which provides a barrier or an insulating area against the short circuiting of the terminals.

In order to prevent completion of a conducting moisture film between the adjacent terminals 22, applicant has provided radial furrows, two of which, 30 and 31, are diametrically opposite and extend from the central terminal outwardly to the inner surface of the annular wall of the cup-shaped distributor cap, as shown in Figs. 2 and 3. It will be noted that radial furrows 30 and 31 cut across the annular furrows 25, 26 and 27, thus again presenting an impedance against undue accumulation of moisture on the annular ridges formed by the annular furrows mentioned. Such undue accumulation might result, if the ignition device is being operated at an angle in which one portion of the distributor cap or head 20 is considerably lower than the other portion. Radial furrows at right angles to the radial furrows 30 and 31 as shown in Fig. 3 would terminate in the rounded portions 35 of the inner wall adjacent the recess 23 provided in the outer surface of the terminal cap. In order to eliminate this and to have furrows which reach substantially to the outer annular wall of the terminal cap, applicant has provided V-shaped furrows comprising converging branch portions 36, 37 and 36a, 37a adjacent the rounded portions 35. A radial furrow 38 leads from the central terminal 21 and communicates with the furrow comprising branch portions 36 and 37 on the one side, while a similar radial furrow 39 leads from the central terminal 21 and communicates with the opposite furrow comprising branch portions 36a and 37a, so that another impedance to the accumulation of condensed moisture in the annular furrows about the central terminal 21 is presented. It may be seen that the radial furrows 30 and 31 and the V-shaped furrows comprising arms 36, 37 and 36a, 37a will substantially prevent condensed moisture from forming a continued film between any of the terminals 22.

From the foregoing it may be seen that applicant has provided an ignition distributor cap with a sulcated surface presenting a plurality of furrows arranged to prevent the formation of a conducting film between either the central terminal and the outside terminals, or between adjacent outside terminals, thus substantially eliminating short circuiting of the sparking impulses due to condensed vapor films within the distributor head.

While the form of embodiment of the present invention as herein disclosed, constitutes a preferred form, it is to be understood that other forms might be adopted, all coming within the scope of the claims which follow.

What is claimed is as follows:

1. A terminal head for an ignition distributor comprising, a body of insulating material; a central terminal in said body, a plurality of spaced terminals in said body, arranged in a circular row about the central terminal; annular furrows in the one surface of the body, substantially concentric with the central terminal; and radial furrows between the spaced terminals arranged in a circular row.

2. A terminal head for an ignition distributor device comprising, a body of insulating material; a central terminal in said body, a plurality of spaced terminals in said body, arranged in a cir-

cular row about the central terminal; annular furrows in the one surface of the body, substantially concentric with the central terminal; and furrows extending radially across the annular furrows and between adjacent terminals arranged in a circular row.

3. A terminal cap for an ignition device comprising a cup-shaped member of insulating material; diametrically opposite recesses in its outer surface; a central terminal exposed interiorly of the cup-shaped member; a plurality of terminals equi-spaced and arranged in a circular row about said central terminal, and so that each aforementioned recess is positioned between two of these terminals; annular furrows in the inner surface of the cup-shaped member, substantially concentric with the central terminal; two oppositely disposed, radial furrows in said surface of the cup-shaped member, extending from the central terminal substantially to the outer annular wall of the cup-shaped member; a furrow in said surface of the cup-shaped member, adjacent each recess in its outer surface, each furrow comprising converging branch portions; and a radial furrow leading from the apex of the converging branch portions of each of said last-mentioned furrows, across the annular furrows to the central terminal.

4. A terminal cap for an ignition device comprising a cup-shaped member of insulating material, a central terminal exposed interiorly of the cup-shaped member; a plurality of terminals equi-spaced and arranged in a circular row about said central terminal; a series of circumferential furrows arranged within said cup-shaped member, spaced apart and interposed between said central terminal and the circular row of terminals; a plurality of radial furrows extending from the central terminal to the outer annular wall of said cup-shaped member, each of said radial furrows being spaced and interposed between successive terminals arranged in the circular row.

5. A terminal cap for an ignition device comprising, a cup-shaped body of insulating material; a central terminal in said body; a plurality of spaced terminals in said body arranged in a circular row about the central terminal; a series of circumferential projections arranged within said body spaced apart and interposed between said central terminal and the circular row of terminals, the edge of each successive projection following the projection nearest the central terminal extending below the edge of the preceding projection; and a plurality of radial recesses extending from the central terminal to the outer wall of said cup-shaped member, said recesses being arranged so that a recess is located between successive terminals arranged in the circular row.

6. A terminal support comprising a body of insulating material and having extending from one side thereof a plurality of separated terminals to which electrical conductors are adapted to be connected, means for preventing the formation by condensation of a continuous film of liquid on the surface of the insulating material between the terminals, said means comprising a plurality of V-shaped grooves between the terminals of such depth that the condensate will not fill the grooves.

7. A terminal support comprising a body of insulating material and having extending from one side thereof a plurality of separated terminals to which electrical conductors are adapted to be connected, means for preventing the formation by condensation of a continuous film of

5 liquid on the surface of the insulating material between the terminals, said means comprising a plurality of relatively deep and narrow grooves between the terminals, said grooves being of such a size and having such a ratio between depth and width that condensate will not cover the surface of such grooves sufficiently to form a continuous liquid film between the terminals.

8. A terminal support comprising a body of 10 insulating material and having extending from one side thereof a plurality of separated terminals to which electrical conductors are adapted to be connected, means for preventing the formation by condensation of a continuous film of 15 liquid on the surface of the insulating material between the terminals, said means comprising a plurality of relatively deep and narrow grooves between the terminals and a series of sharp ridges separating the grooves, said grooves being 20 of such a size and having such a ratio between depth and width that condensate will not cover the surface of such grooves sufficiently to form a continuous liquid film between the terminals.

9. A terminal support comprising a body of 25 insulating material and having extending from one side thereof a central terminal and a plurality of spaced terminals arranged in a circular row about the central terminal and spaced therefrom, means for preventing the formation by 30 condensation of a continuous film of liquid on the surface of the insulating material between the terminals, said means comprising a plurality of relatively deep and narrow grooves extending around the central terminal and lying between 35 said central terminal and the other terminals, and a series of sharp ridges separating said grooves, said grooves being of such a size and having such a ratio between depth and width that the condensate will collect on said ridges 40 and will not cover the surface of said grooves sufficiently to form a continuous liquid film between the terminals.

10. A terminal support comprising a body of 45 insulating material and having extending from one side thereof a central terminal and a plurality of spaced terminals arranged in a circular row about the central terminal and spaced therefrom, means for preventing the formation by 50 condensation of a continuous film of liquid on the surface of the insulating material between the

terminals, said means comprising a plurality of alternate grooves and ridges of V-shape extending around the central terminal and lying between said central terminal and the other terminals, said grooves being of sufficient depth to prevent the condensate from covering the surface of said grooves sufficiently to form a continuous film of liquid between the terminals.

11. A terminal head for an ignition distributor comprising a body of insulating material, a central terminal in said body adapted to be connected to the ignition coil, a plurality of spaced terminals in said body arranged in a circular row about the central terminal and adapted to be connected to the spark plugs of an internal combustion engine, means for preventing the formation, by condensation, of a continuous film of liquid on the surface of said insulating material between the center terminal and the other terminals, said means comprising a plurality of 10 relatively deep and narrow grooves extending around the center terminal and lying between the center terminal and said circular row of terminals, said grooves being of such size and having such a ratio of depth to width that the 15 condensate will not cover the surface of the grooves sufficiently to form a continuous liquid film between the center and outer terminals.

12. A terminal head for an ignition distributor comprising a body of insulating material, a central terminal in said body adapted to be connected to the ignition coil, a plurality of spaced terminals in said body arranged in a circular row about the central terminal and adapted to be connected to the spark plugs of an internal combustion engine, means for preventing the formation, by condensation, of a continuous film of liquid on the surface of said insulating material between the center terminal and the other terminals, said means comprising a plurality of relatively deep and narrow V-shaped grooves extending around the center terminal and lying between said central terminal and the other terminals, said grooves being of sufficient depth to prevent the condensate from covering the surface of the grooves sufficiently to form a continuous liquid film between the center and outer terminals.
